DECORATIVE GRILLEWORK

Robert Titus Bogan, Jr., 2031 Somervell NE.
Albuquerque, N. Mex. 87112

Filed Oct. 11, 1965, Ser. No. 87,434

Term of patent 14 years

(Cl. D13—1)

Fig. 1

FIG. 1 is a front elevation of a portion of a decorative grillework embodying my new design, with rear being substantially the same in appearance except that the sets of crossing diagonal grooves on the rear being interspersed with the sets of crossing diagonal grooves on the front, with the grillework pattern repeating as indicated by the broken lines;

FIG. 2 is a front elevation, on a larger scale, of a portion of the grillework shown in FIG. 1;

FIG. 3 is a vertical section, taken along line 3—3 of FIG. 2;

FIG. 4 is an oblique section, taken along line 4—4 of FIG. 2; and

FIG. 5 is a horizontal section, taken along line 5—5 of FIG. 2.

I claim:

The ornamental design for a decorative grillework, as shown and described.
